UNITED STATES PATENT OFFICE

BRUCE W. HOOVER, OF OAKLAND, CALIFORNIA

DESIGN FOR A SERVICE STATION

Application filed January 16, 1929. Serial No. 29,634. Term of patent 7 years.

To all whom it may concern:

Be it known that I, BRUCE W. HOOVER, a citizen of the United States, and a resident of the city of Oakland, county of Alameda, State of California, have invented a new, original, and ornamental Design for Service Station, of which the following is a specification, reference being had to the accompanying drawing, forming part thereof.

Figure 1 is a side view of the service station illustrating my new design.

Figure 2 is a front view of the service station.

Figure 3 is a plan view of the service station.

I claim:

The ornamental design for a service station substantially as shown.

BRUCE W. HOOVER.
